REFRIGERATING APPARATUS

Harry B. Hull, Dayton, Ohio, assignor, by mesne assignments, to General Motors Corporation, a corporation of Delaware

Application May 28, 1930, Serial No. 456,682

4 Claims. (Cl. 62—6)

This invention relates to refrigerating apparatus and methods and particularly to that type of apparatus and method which maintains automatically two zones at different temperatures.

5 An object of this invention is to provide a method and apparatus for maintaining two or more zones at different temperatures by means of a closed circulating system containing a volatile refrigerant at the same pressure throughout the 10 closed system and in which the operation of the closed system is controlled in accordance with temperature conditions prevailing in the warmer zone.

Further objects and advantages of the present 15 invention will be apparent from the following description, reference being had to the accompanying drawing, wherein a preferred form of the present invention is clearly shown.

In the drawing:

20 The figure is a view, partly in vertical cross-section, partly in elevation, and partly diagrammatic, of an apparatus embodying features of this invention.

According to this invention, two or more zones 25 may be maintained at relatively low and relatively higher refrigerating temperatures by cyclicly exposing a volatile refrigerant to a vaporizing action in one of said zones and condensing the refrigerant in another of said zones, while said 30 refrigerant is maintained throughout at substantially the same pressure, by utilizing temperature conditions in the warmer zone for restricting the normal flow of refrigerant, or for varying the amount of liquid refrigerant available for cooling 35 said second zone.

Features of this invention may thus include 40 means for maintaining a first zone 20 at a relatively low temperature and means 22 for maintaining a second zone 21 at a higher temperature. The means 22 preferably is a closed circulating 45 system, which may contain a volatile refrigerant substantially at the same pressure (neglecting slight hydrostatic heads) throughout the closed system 22. Means 22 may also include an evaporator 23 adapted to perform the cooling for the 50 zone 21. The means 22 may also include a condenser 24 in the first zone 20. A connection for the flow of refrigerant between the evaporator and the condenser may include a liquid line 25 and a vapor line 26 so that refrigerant condensed 55 in the condenser 24 may flow through the line 25 to the evaporator 23 and the refrigerant evaporated in the evaporator 23 may pass as a vapor through the vapor line 26 to the condenser 24.

55 The normal flow of refrigerant between the condenser 24 and the evaporator 23 may be varied in accordance with temperature conditions in the warmer zone 21. That is, the flow which normally would take place under temperature 60 conditions prevailing in the apparatus may be

varied in order to maintain the desired temperature condition in the zone 21. As a specific example, means 27 responsive to temperature conditions in the zone 21 may be provided for varying the normal flow of refrigerant. Preferably this normal flow of refrigerant is varied in the vapor line 26 by throttling the flow of vaporized refrigerant in the vapor line 26. This may be accomplished by providing a bellows 28, responsive to pressure conditions in the thermostatic bulb 29 10 for operating the means or valve 27 in the vapor line. Thus it is to be seen that when the valve 27 partly or completely throttles the line 26, further evaporation in the evaporator 23 causes liquid refrigerant from the evaporator to flow in the 15 line 25 towards the condenser 24. This varies the amount of liquid refrigerant in the evaporator 23 and thus varies the cooling capacity of the evaporator.

A manual adjustment 33 may be provided for 20 varying the setting of the bulb 29 in order that the user may selectively regulate the temperature of the zone 21.

The zone 20 may be maintained at a relatively 25 low temperature by any suitable means. Thus a float controlled evaporator 34 may be placed in thermal contact with the condenser 24. The evaporator 34 may be refrigerated by any suitable means. Thus it may be refrigerated by providing a float valve and outlet fitting 35 of the 30 well-known construction, for instance as shown in the patent to R. G. Osborn, 1,556,708 which expands refrigerant entering from the pipe 36 into the evaporator 34. The expanded refrigerant may pass through the pipe 37 from the evaporator 34 to any suitable liquefying means such as a compressor 38 which delivers compressed refrigerant to a condenser 39 discharging into a liquid refrigerant receiver 40. The receiver 40 may be connected by means of a pipe 37 with 40 the evaporator 34.

The zone 20 may be maintained at any desirable predetermined temperature. Thus it may be maintained at a substantially constant temperature between predetermined temperature 45 limits by any suitable means such as by making the operation of the compressor dependent on temperature conditions within the evaporator 34. For this purpose bellows 42 may be connected to the pipe 37 and may operate a snap switch 44 50 which controls the starting and stopping of the motor 41 which drives the compressor 38. This maintains the zone 20 within predetermined temperature limits.

If the zones 20 and 21 are part of a domestic 55 mechanical refrigerator, it may be desirable to provide means for freezing ice cubes or the like. This may be accomplished by providing ice cube trays 58 in proper sleeves within the evaporator 34. The zone 21 may be formed by the lining 52, 60

which forms a food compartment and is insulated by means of the insulation 53. The zone 20 may be insulated from the zone 21 by means of the loose insulation 54.

5 In this particular embodiment the evaporator 23 is adapted to be maintained at a predetermined temperature by the action of the means 27. Thus when the zone 21 is cooled to a predetermined temperature, the pressure in the thermostatic bulb 29 drops to such a point that the valve 27 is partly or wholly closed. Any evaporation in excess of that required to maintain the predetermined temperature tends to create an excessive amount of vapor in the upper part of the evaporator 23. This forces liquid refrigerant through the insulated pipe 25 towards the condenser 24. Since the amount of liquid refrigerant in the evaporator 23 is thusly reduced the cooling action of the evaporator on the zone 21 is reduced. On 10 the other hand, when the temperature of the zone 21 rises, the pressure in the thermostatic bulb 29 also rises so that the valve 27 is opened and permits all of the liquid refrigerant possible to flow into the evaporator 23. This increases the cooling power of the evaporator to its maximum capacity at the refrigerant temperature prevailing. This action tends to maintain the average temperature of the zone 21 substantially constant. This permits the maintenance of the food compartment at any desired temperature independently of the temperature prevailing in the zone 20.

While the form of embodiment of the invention as herein disclosed constitutes a preferred form, it is to be understood that other forms might be adopted, all coming within the scope of the claims which follow.

What is claimed is as follows:

1. A refrigerating apparatus comprising in combination, a cabinet having a food storage compartment and a low temperature zone insulated from said compartment, means for maintaining said zone at a substantially uniform low temperature, means for maintaining said food storage compartment at a relatively higher substantially uniform temperature, said second named means including a closed circulating system containing a volatile refrigerant at substantially the same pressure throughout the closed system and having an evaporator in said food storage compartment and a condenser in said low temperature zone, a liquid line between said evaporator and said condenser, a vapor line between said evaporator and said condenser, and means in said vapor line responsive to temperatures varying from said uniform temperature in said food storage compartment for throttling the flow of refrigerant vaporized in said evaporator to said condenser through said vapor line, said last named means causing liquid refrigerant to flow from said evaporator toward said condenser in said liquid line upon further vaporization thereof in said evaporator.
2. A refrigerating apparatus comprising in combination, a cabinet having a food storage compartment and a low temperature zone insulated from said compartment, means for maintaining said zone at a substantially uniform low temperature, means for maintaining said food storage compartment at a relatively higher substantially uniform temperature, said second named means including a closed circulating sys-

tem containing a volatile refrigerant at substantially the same pressure throughout the closed system and having an evaporator in said food storage compartment and a condenser in said low temperature zone, a liquid line between said evaporator and said condenser, a vapor line between said evaporator and said condenser, a valve in said vapor line for throttling the flow of refrigerant vaporized in said evaporator to said condenser through said vapor line, and means for actuating said valve in response to temperatures varying from said uniform temperature in said food storage compartment, said valve causing liquid refrigerant to flow from said evaporator toward said condenser in said liquid line upon further vaporization thereof in said evaporator. 5

3. A refrigerating apparatus comprising in combination, a cabinet having a food storage compartment and a low temperature zone insulated from said compartment, means for maintaining said zone at a substantially uniform low temperature, means for maintaining said food storage compartment at a relatively higher substantially uniform temperature, said second named means including a closed circulating system containing a volatile refrigerant at substantially the same pressure throughout the closed system and having an evaporator in said food storage compartment and a condenser in said low temperature zone, a liquid line between said evaporator and said condenser, a vapor line between said evaporator and said condenser, means in said vapor line responsive to temperatures varying from said uniform temperature in said food storage compartment for throttling the flow of refrigerant vaporized in said evaporator to said condenser through said vapor line, said last named means causing liquid refrigerant to flow from said evaporator toward said condenser in said liquid line upon further vaporization thereof in said evaporator, and manually actuated adjustable means for varying the temperature at which said last named means becomes effective. 35

4. A refrigerating apparatus comprising in combination, a cabinet having a food storage compartment and a low temperature zone insulated from said compartment, means for maintaining said zone at a substantially uniform low temperature, means for maintaining said food storage compartment at a relatively higher substantially uniform temperature, said second named means including a closed circulating system containing a volatile refrigerant at substantially the same pressure throughout the closed system and having an evaporator in said food storage compartment and a condenser in said low temperature zone, a liquid line between said evaporator and said condenser, a vapor line between said evaporator and said condenser, a valve in said vapor line for throttling the flow of refrigerant vaporized in said evaporator to said condenser through said vapor line, means for actuating said valve in response to temperatures varying from said uniform temperature in said food storage compartment, said valve causing liquid refrigerant to flow from said evaporator toward said condenser in said liquid line upon further vaporization thereof in said evaporator, and manually actuated means for varying the temperature at which said last named means becomes effective to actuate said valve. 50
